TRAVELING WAVE AMPLIFIER

André G. Clavier and Etienne C. de Faymoreau,
 New York, N. Y., assignors to International
 Standard Electric Corporation, New York, N. Y.,
 a corporation of Delaware

Application March 27, 1947, Serial No. 737,602

7 Claims. (Cl. 179—171)

1

This invention relates to wave transmission systems and more especially to systems for the amplification of broad frequency bands of high frequency energy.

A principal object of the invention is to provide a wave transmission system wherein at least one electron discharge device is employed, the electron trajectories within the device and the initial electron velocity being correlated with the electric field between the transmission line conductors at the region where the device is connected, so as to achieve selective frequency amplification of waves in a given frequency range which are propagated in one direction along the line, as compared with waves of the same frequency range propagated along the line in the opposite direction.

Another object is to provide an improved electron tube of the travelling wave type which has asymmetrical transmission characteristics for the same frequency range to be propagated through the device in opposite directions.

Another object is to provide an improved two-way high frequency wave transmission system employing one or more travelling wave tubes of novel construction.

Another important object is to provide an electron tube of the travelling wave type having means to control its transmission properties by controlling the electron trajectories from the cathode so as to impart asymmetrical conductive properties to the tube when it is used as a high frequency transmission line section.

A feature of the invention relates to a high frequency transmission line unit comprised of a convoluted transmission line section between the conductors of which an electron discharge is set up, and means are provided to adjust the electron trajectories at a predetermined angle to the wave propagational axis of the line to impart to said line section selective amplifying properties for waves of a selected frequency range.

Another feature relates to an electron discharge tube enclosing an electron emitter which is surrounded by a convoluted transmission line together with means to adjust the initial velocity and trajectory of the electron stream between the line conductors within the tube to cause the tube to have selective amplifying powers for waves of a selected frequency propagated along the line in one direction, and to have selective amplifying powers for waves of different selected frequency propagated along the line in the opposite direction.

Another feature relates to an electron tube of

the travelling wave type wherein an electron emitter is provided with a pair of cooperating electrodes which form a convoluted transmission line.

A further feature relates to an electron tube having an elongated central emitting cathode which is surrounded by a convoluted transmission line section, the outer conductor of the said line section being tubular and having that portion of its periphery near the cathode, of open-work construction.

A further feature relates to a novel construction of electron tube which has the property of acting as a two-way amplifier without danger of singing.

A still further feature relates to the novel arrangement and correlation of parts and electric parameters for producing an improved two-way ultra high frequency wave transmission and amplifying system.

Other features and advantages will appear from the following detailed descriptions and the appended claims.

In the drawing,

* Fig. 1 is a schematic diagram of a generic high frequency wave transmission system to which the invention is applicable.

Fig. 2 is a schematic diagram of a system according to the invention and showing the novel travelling wave tube which also forms part of the invention.

Fig. 3 is a detailed view of the convoluted transmission line section of the tube of Fig. 2.

Fig. 4 is an end view of the tube of Fig. 2.

Fig. 5 is an enlarged perspective view of part of Fig. 2.

Fig. 6 is a schematic illustration of a modification of the tube of Fig. 4.

Fig. 7 is a modification wherein the signal transmission is effected by an electrode acting as a wave guide.

Referring to Fig. 1, there is shown in schematic form, the general type of system to which the present invention is applicable. It comprises a source 10 of high frequency wave energy, a high frequency load device 11, and an intervening transmission line 12. The load device is matched to the surge impedance of the transmission line so as to avoid the setting up of standing waves therealong. Interposed in this line at any suitable region thereof is an electron discharge device 13, comprising an electron-emitting cathode 14, a foraminous conductive member 15, and a collector electrode 16. The collector electrode is coupled to one of the line conductors, for ex-

ample through the intermediary of the overlapping quarter-wave line sections 17, 18; and member 15 is connected as an effective continuation of the other line conductor. Preferably, although not necessarily, the members 15 and 16 are at the same D. C. potential, and the cathode 14 is negatively biassed with respect thereto so as to impart a predetermined initial electron velocity to the electrons which travel transversely between the electrodes 15 and 16. With this arrangement the transmission line conductors can be held at D. C. ground potential. If the physical length of the members 15 and 16, considered as reflectionless extensions of the transmission line conductors, is substantially greater than the wave length of the waves from source 10, then by interaction between the electric field of these waves and the electrons between the transmission line conductors within the tube 13, these waves are boosted in amplitude. By adjusting the initial velocity and transit time of the electrons, there is produced a negative leakance effect along the line at the region where device 13 is located. For a detailed description of this type of transmission line arrangement, reference may be had to application Serial No. 726,343; filed February 4, 1947, now abandoned.

The tube 13 operates as an amplifier equally well in both directions, but it necessitates very good impedance matching at both ends of the device 13 with the respective transmission line sections. More precisely, when the reflected portion of a travelling wave propagated along the line happens to fall in phase with the incoming wave at the input of tube 13, the condition for stability will be

$$A^2r < 1$$

in which A is the volt amplification ratio of the tube, and r the reflection coefficient at the output end of the tube. This means that if the matching can be arranged so that $r=0.1$, A cannot exceed 10. In order to overcome this limitation, and in accordance with this invention, the electrons from cathode 14 traversing the space between 15 and 16 have a predetermined initial velocity having an axial component considered along the propagational axis of the transmission line.

A theoretical investigation shows that as a first approximation, the same negative leakance effects can be obtained as in the arrangement of application Serial No. 726,343, but the frequencies limiting the regions where such an effect is obtained, are determined by the following expressions:

$$\frac{l}{v_{ox}(1-m)} f_1 = 1$$

$$\frac{l}{v_{ox}(1-m)} f_2 = \frac{3}{2}$$

while in the previous case the corresponding formulae were:

$$\frac{l}{v_{ox}} f_1 = 1$$

$$\frac{l}{v_{ox}} f_2 = \frac{3}{2}$$

In these equations l is the distance between the conductors of the transmission line, v_{ox} is the initial speed of electrons in the direction perpendicular to the axis of the line, and m is the ratio of the initial speed of electrons in the axial direction to the speed of the travelling wave.

For the wave travelling in the opposite direction, the same formulae will apply except that $1-m$ will become $1+m$. A suitable choice for factor m will thus provide a means to separate the range of frequencies which is amplified in one direction, say east to west, from the range of frequencies which will be amplified in the reverse direction; say west to east. The best initial velocity is at 45° to the direction of the propagational axis of the line, in order to bring the effect of the magnetic field of the travelling wave in cooperative phase with the effect of the electric field.

Referring to Figs. 2 to 5, there is shown one preferred arrangement for controlling the initial electron velocities and trajectories to achieve the desired asymmetric transmission characteristics. In Fig. 2, the source 10 of ultra frequency wave signals is connected to the load 11 via transmission line 12, which is preferably of the coaxial or wave guide type. Interposed in, and forming part of, this transmission line is an electron discharge tube 21 which, according to the invention, comprises an evacuated glass envelope or bulb 22 having centrally supported therein an electron-emitting cathode sleeve 23, provided with an internal heater wire 24 in the manner well-known in electron tubes of the indirectly heated cathode type. The cathode sleeve 23 is provided with a lead-in 25 and separate lead-ins 26, 27 are provided for supplying current to the cathode heater.

Concentrically surrounding the cathode throughout its length is a convoluted transmission line section comprising an outer tubular or hollow conductor 28, within which is insulatingly supported by insulator beads 29, the central conductor 30. If desired, the conductor 30 may have lateral conductive fins or wings 31, 32, to provide the desired capacitance between the line conductors and thereby to effect any desired slowing down of the travelling waves which are propagated along the line between the conductors. The wall portion 33 of conductor 28 adjacent cathode 23 is of open-work construction such as wire mesh so as to enable the electrons emitted from the cathode 23 to flow between the said line conductors 30 and 33. The members 30 and 33 are suitably biassed with respect to the cathode 23, for example by the battery 34, so as to impart the desired initial electron velocity to the emitted electrons. In certain special cases it may be desirable to apply a different D. C. bias to members 30 and 33 as indicated by the connection to the battery 34 (Fig. 2), a positive terminal of which may be grounded.

Suitably supported with relation to tube 22 is a magnet 35 to provide a magnetic field of constant strength. The tube 22 is supported so that the central longitudinal axis thereof is in line with the field between the magnet poles 36, 37. By this arrangement the electron trajectories between line conductors 30 and 33 of this section will have the desired inclination with respect to the electrical field existing between these conductors which electric field is of course determined by the signals applied to the transmission line section from source 10. The said inclination of the electron trajectories will be determined by radial spacing of the cathode 23 and the conductor 30 and by the strength and direction of the magnetic field. As pointed out above, if the cathode 23 and the convoluted section 28 have physical lengths which are substantially greater than the wave length of the sig-

nals from source 10, the electron streams between conductors 30 and 33 will be subjected to velocity modulations during their transverse motion between conductors 30 and 33, with the result that for suitable adjustment of the electron initial velocities and trajectories, the signals are subjected to amplification as they are propagated through the tube. One possible explanation of this effect is that the average kinetic energy of the electrons during each period of the travelling wave is decreased. The corresponding loss of energy in the electron beam is transferred to the electromagnetic field of the wave which is thus amplified as it travels along the tube.

With this arrangement, the operation of the tube for a definite frequency range from source 10 may be amplified, is substantially entirely electronically controlled and the selective transmission is effected by adjusting the initial electron velocity for correct electron transit time between the conductors 30, 33, and by the correct initial electron direction. Preferably, the transit time is adjusted to between 2π and 3π radians.

While Fig. 2 shows a one-way transmission system, it will be understood that the tube 22 can be connected so as to form part of a simultaneous two-way transmission system. By the adjustment of the initial velocity of the electrons and their inclined trajectories as above described, provision can be made for a range of frequencies to be selectively amplified in the east-west direction, and a separate range of frequencies to be selectively amplified in the west-east direction, without danger of singing in the tube. Thus, the transmission line can be used in both directions in a manner analogous to two-way telephony systems. The arrangement therefore is useful in a relay station of a radio link in which case the tube 22 has the opposite ends of the convoluted transmission line section connected to suitable high frequency pick-up antennae and associated with each such antenna is a corresponding parabolic reflector.

Fig. 6 shows a modification of Fig. 5, wherein the two transmission line conductors consist of a hollow coiled tubular member 28 with the portion of its periphery facing the cathode 23 in the form of a wire mesh 30a, which mesh however is supported at its longitudinal edges by insulator beads 38, so as to be insulated from the portion 28, so far as the high frequency transmission signal currents are concerned. In other words, elements 31a and 28 constitute a helically coiled two-conductor high frequency transmission line, the foraminous portion of which faces the cathode 23, the transmission line being suitably biased with respect to the cathode so as to produce the desired electron velocities between elements 38a and 28. It is understood of course that a constant intensity magnetic field is produced with respect to the electron trajectories in the same manner as illustrated in the embodiment of Fig. 2, for example by magnet 35, and the coiled line and cathode are mounted within an evacuated envelope.

The invention is not limited to a system employing a transmission line of the coaxial type, or of the two-conductor type. It is equally well applicable to a transmission line of the wave guide type. Such an arrangement is schematically illustrated in Fig. 7, in which the wave guide consists of a helically convoluted tubular member similar to the member 28 but with the cen-

tral conductor 30 omitted. This coiled member coaxially surrounds the electron-emitting cathode 23, and the portion 30a of the periphery of member 28 facing the cathode is of foraminous or open-work construction such as wire mesh. In Fig. 7, the foraminous section 30b which faces the cathode is in D. C. conductive relation with the portion 28 to form a suitable wave guide and this wave guide is suitably biased with respect to cathode 23 to provide the desired initial electron velocity from the cathode traversing the space between 30b and 28. It will be understood of course, that the coiled wave guide is suitably mounted together with the cathode in an evacuated receptacle as in the embodiment of Fig. 2. Likewise, a constant magnetic field is provided, for example by a magnet similar to magnet 35, to provide the necessary inclined electron trajectories.

While particular embodiments have been disclosed herein, it will be understood that various changes and modifications may be made therein without departing from the spirit and scope of the invention.

What is claimed is:

1. A device for amplifying the energy of a high frequency wave comprising a pair of spaced conductors of elongated form, a cathode disposed adjacent said conductors, input coupling means to apply high frequency wave energy to said conductors for propagation therealong, output coupling means to take off wave energy from said conductors, means to bias at least one of said conductors positively with respect to said cathode to effect a flow of electrons between said cathode and said one conductor and means for producing a magnetic field substantially at right angles to the disposition of said conductors to effect inclination of the projectory of said electrons in a direction lengthwise of said conductors, said biasing means including connections for biasing both of said conductors, said biasing means including means for biasing one of said conductors at a higher potential than the other.
2. A device for amplifying the energy of a high frequency wave comprising a pair of spaced conductors of elongated form, a cathode disposed adjacent said conductors, input coupling means to apply high frequency wave energy to said conductors for propagation therealong, output coupling means to take off wave energy from said conductors, means to bias at least one of said conductors positively with respect to said cathode to effect a flow of electrons between said cathode and said one conductor and means for producing a magnetic field substantially at right angles to the disposition of said conductors to effect inclination of the projectory of said electrons in a direction lengthwise of said conductors, one of said conductors being at least in part interposed between the other of said conductors and said cathode and the interposed part being foraminous to permit the passage of electrons from said cathode into the space between said conductors.
3. A device for amplifying the energy of a high frequency wave comprising a pair of spaced conductors of elongated form, a cathode disposed adjacent said conductors, input coupling means to apply high frequency wave energy to said conductors for propagation therealong, output coupling means to take off wave energy from said conductors, means to bias at least one of said conductors positively with respect to said cathode to effect a flow of electrons between said cath-

ode and said one conductor and means for producing a magnetic field substantially at right angles to the disposition of said conductors to effect inclination of the trajectory of said electrons in a direction lengthwise of said conductors, said conductors comprising a wave guide with one of the conductors disposed within the other and the side of the conductor nearest said cathode being provided with openings therethrough for the passage of said electrons from 10 said cathode to the inner conductor.

4. A traveling wave amplifier comprising magnetic means for producing a magnetic field, a cathode of elongated form disposed coaxially of said field, a wave guide comprising an inner and 15 an outer conductor disposed in the form of a helix about said cathode whereby the lines of force of said magnetic field are substantially normal to the turns of said wave guide, the side of the outer conductor adjacent said cathode being 20 of open-work construction for the passage of electrons and means for biasing at least one of said conductors positively with respect to said cathode.

5. A traveling wave amplifier according to claim 25 4, wherein said inner conductor includes at least one vane capacitively spaced from the outer conductor.

6. A traveling wave amplifier according to claim 4, wherein said biasing means includes connections for biasing both of said conductors positively with respect to said cathode.

7. A traveling wave amplifier according to claim 6, wherein said biasing means includes means for biasing the inner conductor at a more positive potential than said outer conductor.
